UNITED STATES PATENT OFFICE.

JOHN GARDNER, OF NEW HAVEN, CONNECTICUT, ASSIGNOR TO WINCHESTER REPEATING ARMS CO., OF NEW HAVEN, CONNECTICUT, A CORPORATION.

PRIMER FOR CARTRIDGES.

SPECIFICATION forming part of Letters Patent No. 733,638, dated July 14, 1903.

Application filed May 1, 1903. Serial No. 165,116. (No model.)

To all whom it may concern:

Be it known that I, JOHN GARDNER, of New Haven, in the county of New Haven and State of Connecticut, have invented a new and useful Improvement in Primers for Cartridges; and I do hereby declare the following, when taken in connection with the accompanying drawings and the letters of reference marked thereon, to be a full, clear, and exact description of the same, and which said drawings constitute part of this specification, and represent, in—

Figure 1, a view in longitudinal section of a primer constructed in accordance with my invention; Fig. 2, a rear view thereof.

My invention relates to an improvement in primers for cartridges, and constitutes an improvement upon the primer shown and described in United States Patent No. 653,953, granted July 17, 1900, upon my application, the object being to produce a primer for cartridges of superior strength, increased delicacy of fire, and constructed with particular reference to safety in being handled and packed.

With these ends in view my invention consists in a primer for cartridges having certain details of construction and combinations of parts, as will be hereinafter described, and pointed out in the claim.

In carrying out my invention as herein shown I employ a stamped sheet-metal anvil 2, formed at its inner end with a detonating nose 3 and at its outer end with a deep wide notch or cut 4, providing a flame-vent which permits the free escape of the flame from the detonating composition 5 to the powder in the cartridge. The parallel edges or sides 6 of the anvil are formed with corresponding stop-shoulders 7, located directly opposite each other and at a right angle to the longitudinal axis of the anvil. In assembling the primer these shoulders are brought to a solid bearing upon the square edge of a sheet-metal anvil-supporting and fulminate-receiving cup 8, the bottom of which forms the primer-head proper and is preferably slightly crowned, as shown, to increase its strength, though that is not necessary. It will be

readily understood that the stop-shoulders 7 in their bearing upon the square edge of the cup 8 positively and definitely establish the position of the nose 3 of the anvil in relation to the detonating composition 5. By changing the distance of the stop-shoulders 7 from the nose 3 or by varying the depth of the cup 8 the extension of the nose 3 into the fulminate may be regulated with the greatest nicety. The stop-shoulders 7 are held solidly against the square edge of the cup 8 by crimping the open end of the primer-shell 9 inward and down over the outer end of the anvil, so as to form a retaining flange or crimp 10, which then coats with the stop-shoulders 7 and the edge of the cup 8 to rigidly hold the anvil 2 against displacement in either direction under any handling or usage that the primer may be subjected to, whereby its accidental detonation is surely avoided. The shell 9 is bent upon itself at its rear end to form a head-flange or primer-rim 11, which limits the depth to which the primer may be seated in the pocket formed for its reception in the head of the cartridge. After the rim 11 has been produced the end of the shell is centrally cut away to form a large circular opening 12 to expose the convex bottom of the cup 8. It will be observed by reference to Fig. 1 of the drawings that the corner of the cup 8 fits into the inside of the rim 11, so that the shell reinforces and strengthens the cup 8, which ordinarily will be made of softer metal than the shell. In this way added strength is secured and increased delicacy of fire attained, for the bottom of the cup forms the head proper of the primer and being softer than the shell secures the delicacy of fire referred to.

A primer constructed in accordance with my invention and having its anvil positively held against the slightest movement in either direction in any handling to which a primer may be subjected thereby becomes perfectly safe so far as any danger of ignition due to the movement of the anvil is concerned. This provision for increased safety has become more and more important on account of the heavy charges of fulminate which are

necessary to the proper ignition of the denser kinds of smokeless powder. These heavier charges of fulminate also call for stronger primer structures, and such a structure I 5 have secured by the addition of the cup 8, which also performs the additional function of supporting the anvil against inward movement.

Having fully described my invention, what 10 I claim as new, and desire to secure by Letters Patent, is—

In a primer for cartridges, the combination with a shell formed at its rear end with a rim and a large central opening and having its 15 opposite end crimped to form an anvil-retaining flange, of an anvil formed at its inner end with a denotating nose, at its outer end with a cut or notch and on its parallel

side edges with stop-shoulders, and an anvil-supporting and fulminate-receiving cup located within the said shell and having its outer edge engaged by the said stop-shoulders which are solidly held against the said edge by the retaining-flange of the shell which is turned down upon the outer end of the anvil 25 which is thereby positively and definitely held against any longitudinal movement in either direction.

In testimony whereof I have signed this specification in the presence of two subscribing witnesses.

JOHN GARDNER.
